UNITED STATES PATENT OFFICE

2,599,308

DRIVE UNIT FOR DOMESTIC IRONING MACHINES OR THE LIKE

Joseph C. Worst and Carl S. Dayton, Bridgeport, Conn., assignors to General Electric Company, a corporation of New York

Application December 2, 1949, Serial No. 130,656

10 Claims. (Cl. 38—25)

1

Our invention relates to an improved domestic ironing machine of the type having mutually cooperating buck and shoe elements between which the articles are pressed, and particularly relates to improved means for timing the operation of one of the pressing elements with respect to the approach of the other element to ultimate operating position.

The objects of our invention include the provision of improved means for automatically operating the buck and the shoe in a predetermined timed relationship; the provision of driving means common to both elements and simultaneously biasing the same to operating position; the provision of simple, effective means for delaying the operation of one pressing element until the other has reached operating position notwithstanding the employment of a common driving means; and the provision of means utilizing the driving means for effectively controlling the return of the respective pressing elements to their non-operative or "home" position.

A presently preferred embodiment of our invention provides a frame structure arranged to have a table-like working surface on which is located a main cylinder unit of a hydraulic motor system. The motor unit includes a piston unit suitably carrying the buck structure for movement between a "home" or retracted position and a projected or operating position. To propel the piston for projection of the buck into operating position we have found it expedient to use the hydraulic pressure generator which is shown in similar relationship in the Wardwell, Jr., Patent No. 2,135,268, granted November 1, 1938, for "Ironing Machine." We mount the conventional heated shoe on a relatively conventional U-shaped arm or carriage pivoted relative to the buck—as by pivotal attachment to the main cylinder—so that the shoe carriage may be swung in a plane transversely of the buck to bring the shoe from its home position into an operative position in registry with the buck. We operate the shoe carriage from a piston operating within a second cylinder which is in communication with the first. An important feature of our invention resides in utilizing the single fluid pressure generating means for the propulsion of both pistons while effecting the movement of the respective press elements in a predetermined timed relationship. Because in the type of ironer which we have chosen for exemplifying our invention the buck is driven upwardly against the previously positioned shoe, we provide means for holding the buck against movement during the operation of

2

the shoe carriage, and automatically release the holding means by shoe carriage action as the carriage comes into its operating position. Following the release of the buck it will be driven upwardly into pressing relationship with the shoe by the operation of its piston. In this manner, we insure that the shoe will be in position for accurate registry with the buck. In types of ironers in which the shoe exerts pressure against a previously positioned buck, our invention could as readily be adapted to restrain the shoe until the buck had been positioned. An effective feature of our invention derives from check valve means which immediately upon upward movement of the buck closes against return flow of hydraulic fluid from the shoe cylinder so as to provide a locked body of liquid holding the shoe and its carriage firmly in position during the pressing operation. The check valve maintains the shoe carriage in its elevated position until means controlled by the return of the buck piston substantially to its home position opens the valve to permit return flow from the shoe carriage cylinder to the main cylinder. The carriage is thus permitted to return to its home position. The controlled liquid flow provides effective fluid dampeners for cushioning the return movement of the buck and shoe and thus eliminates the necessity for the usual arrangement of dampening springs or dashpot accessories.

Further features and advantages of the invention will be apparent from the accompanying drawing, read in connection with the annexed specification. In the drawing, Fig. 1 is a partial side elevation of an ironing machine embodying our invention, the machine being shown in transverse sectional elevation. Fig. 2 is an enlarged fragmentary view in vertical section of the main and auxiliary piston means, particularly showing the check valve arrangement controlling communication between the main and auxiliary cylinders. Fig. 3 is a fragmentary view showing the flow of fluid from the main cylinder into the shoe operating cylinder passage during the beginning of operation of the machine.

As shown in Fig. 1, the flatplate ironing machine which we have chosen to illustrate our invention includes a rigid frame structure constructed in table-like form to provide a rigid top surface 2. A main hydraulic cylinder 3 is provided with flange means 4 intermediate its ends to afford means by which the cylinder 3 may be affixed to the frame. The flange is angularly related with respect to the cylinder axis so as to support the cylinder in a forwardly inclining

position. It should be understood, however, that when viewed in front elevation the cylinder extends vertically with respect to the table top. Pursuant to conventional flatplate ironing practice the buck 5 is secured to the upper extremity of a piston 6 which operates within the cylinder 3. As is known in the art the buck 5 is generally of elongate rectangular shape, and is padded to provide a cushioned surface on which the articles to be ironed are placed by the operator. Also as is known in the art flatplate ironers utilize a shoe 7 having a smooth, heated ironing surface coextensive with the surface of the buck and arranged to be brought into registry with the buck. For this purpose, the shoe is mounted on a carriage 8 which is pivoted relative to the buck. When the shoe carriage is suitably rotated the shoe is brought into its operating position above the buck and the latter may then be driven upwardly so that the clothes thereon may be pressed between the buck and the shoe. In Fig. 1 the full line representation shows the buck and shoe in a retracted or "home" position and the dotted lines show the respective elements in pressing relationship. It might be noted here that the normal extent of upward movement of the buck is of the order of from $\frac{3}{4}$ inch to 1 inch.

The shoe carriage 8 is desirably of relatively heavy metal stock and is of relatively wide channel-like cross section so as to afford a suitably rigid structure. For pivotally mounting the shoe we have provided ears 9 depending from the cylinder 3 at opposite sides thereof. An extension 10 of each side wall of the shoe carriage 8 registers with the adjacent ear and individual pivot attachments, or a suitable shaft 11 extending from one to the other ear may be employed. It will be obvious that other ways of pivotal mounting of the shoe carriage may occur to those skilled in the art; we have chosen to illustrate what we now consider to be a suitable mounting system.

As previously stated, we incorporate with the piston 6 a hydraulic pressure generating unit which is basically old and well known in the art. In the construction shown in Fig. 2 the piston is provided with a chamber within which is mounted a motor 12 having a shaft extending through a suitable gland to terminate in an impeller 14 operating within a pump chamber 15. It is practical to form the pump chamber by suitably machining out a flange 16 which forms the piston head. Flange 16 is suitably secured to a flange 17 welded or otherwise secured to the body of the piston. The flanges cooperate to receive a piston ring 18. Other flange members disposed intermediate the length of the piston 6 provide for an upper piston ring 20. A central web portion of the flange 17 provides an inlet 21 for the pump housing. It should be understood that the cylinder 3 normally contains a charge of liquid, preferably a light oil, to the approximate level designated O. L. in Fig. 2. The cylinder thus serves additionally as a reservoir of liquid to be drawn on by the pump impeller 14. We provide the usual side wall passages 22 and a foraminated guard screen 23 through which the liquid actually passes to the pump inlet 21. The discharge from the pump travels by way of a passage 24 and ports 25 through the cylinder head to the cylinder space 26 forwardly of the piston head, driving the piston and buck upwardly. Relatively larger ports 27 pass through the piston head assembly externally of the wall of the piston 6 to provide a direct return path

from space 26 to the oil reservoir above the piston head. Controlling said ports 25 and 27 is a slide valve 28 operating within passage 24 and biased by spring 29 normally to close ports 25 and open ports 27. It will be understood that there are preferably two sets of ports and two slide valves. Under the pressure of discharging oil, the valves are urged outwardly to open ports 25 and close ports 27, thus preventing a return of oil to the reservoir from space 26. The piston returns by gravity to home position, the pump having been stopped, and the large return flow ports 27, then open, facilitate return of oil to the reservoir. This valve controlled port arrangement is disclosed and claimed in the copending application of J. F. Young, Serial No. 134,473, filed December 22, 1949, for "Operating Mechanism for Domestic Ironing Machine" and assigned to the assignee of the instant application. It will be understood that the operator controls the motor 12 by any conventional means, such as the usual foot pedal or knee operated switch (not shown).

In ironers of the type shown in the said Wardwell, Jr., Patent No. 2,135,266, motor operation is effective immediately to drive the piston 6 and its thereon mounted buck upwardly into relationship with a shoe which had previously manually been brought into operating position. We provide means for automatically bringing the shoe into registering position before the buck is permitted any substantial rise even though we utilize the pressure generation means of the piston 6 for driving the shoe carriage. As most clearly appears in Fig. 2 we utilize a second cylinder 30 within which operates a conventional piston 31, and operatively connect the piston rod 32 thereof with the shoe carriage 8 by an intermediate pivoted link 33 which is centered with respect to the shoe carriage. A convenient means of securing the link 33 to the shoe carriage is to provide ears 34 depending from the side walls of the carriage, and thread a pivot rod 35 through the ears and link. Spacer sleeves 36 may be carried on the rod and interposed between the side walls of link 33 and the adjacent ears 34 to maintain the centered position of the link. We have shown a screw threaded cylinder head 37 and a piston rod gland 38 although obviously other arrangements are within the scope of those skilled in the art. It will be understood that it is not necessary to have the cylinder 30 carried by the cylinder 3; it is only necessary that cylinder 30 be suitably supported in the frame structure. We believe that manufacturing economies will dictate that cylinder 30 be cast en bloc with cylinder 3. Such an arrangement, for example, makes it practicable to drill the communicating conduit 40 in the thickened head portion of cylinder 3. A remotely disposed cylinder 30 would obviously require the use of tubing or the like, requiring connection fittings and introducing leakage problems. For reasons later explained, we control the communication between the cylinders 30 and 3 by a check valve which prevents return flow from cylinder 30 so long as piston 6 is away from home position. Suitable check valve means may comprise a ball 41 biased by a spring 42 normally to seat against an orifice 43 communicating with the chamber 26. We prefer that with the piston 6 in its home position shown in Figs. 2 and 3 the ball check valve 41 be kept unseated by the engagement therewith of a projection 44 extending from the piston head 16. As indicated in Fig. 3, the initial operation of the pump 14 causes oil to flow

immediately through the orifice 43 into the passage 40 to the cylinder 30, said passage entering the cylinder below the piston 31 as viewed in Fig. 2. In order to recapture any liquid which may work past the piston 31 we provide a communicating port 45 at about the upper operating position of the piston. At each stroke of said piston, oil which may lie thereon passes into the reservoir of cylinder 3.

The timed relationship of the buck and the shoe carriage 8 is accomplished by means restraining the upward movement of the piston 6 during a predetermined extent of movement of the carriage 8. In addition to improving the operation of the ironing machine by accurately timing the operation of one pressing element with respect to the other, our invention imposes no unreasonable burden upon the pressure generator notwithstanding the double duty of the generator as compared with ironers of the type of the said Wardwell patent in which the shoe is manually operated. We may therefore use a small, compact generator. The presently preferred embodiment of our invention utilizes a mechanical latch to hold the piston 6 against movement and provides means responsive to movement of the carriage 8 for tripping the latch when piston operation is to commence. Accordingly, and as somewhat schematically shown in Fig. 1, we provide the piston 6 with an outwardly extending lug 46 of adequate structure and swingably suspend from said lug a latch member 47 which terminates in the latching head 48. For cooperation with the latching head 48 we secure to the table top 2 a rigid block 50 having a suitably notched end portion 51 for engagement with the latching head. A spring 52 suitably carried on the cylinder 3 urges the latch member 47 clockwise of Fig. 1 and therefore tends to maintain the latching head and the block in engagement. By making head 48 suitably longer than the piston travel, the head will always remain in operative relation to the block. It will be understood that the lug 46 is suitably offset with respect to the axis of the cylinder 3 so that the respective latching members may lie alongside of the cylinder 30 as shown in Fig. 1. It will also be understood that a balanced arrangement may be made if desired with a second latch member 47 and block 50 disposed on the opposite side of the cylinder 30.

When the respective pressing elements are in their home position, the latch 47 holds the piston 6 against upward movement. With the piston so held, the impeller provides adequate hydraulic pressure for operation of the piston 31, and the rising piston 31 causes a clockwise rotation of the shoe carriage 8. As the carriage approaches its operating position, it tensions suitable spring means—for example, a leaf spring 54 engaged by the top wall of the carriage—so that when suitable stop means (not shown) establishing the operating position of the shoe arm is reached, spring 54 will have sufficient energy to initiate the return of the carriage at the proper time. To release the latch 47 after the shoe carriage has been brought into operating position we have employed a trip rod 53 on the carriage 8 in alignment with the latch head 48. As the carriage swings into registering position the rod 53 engages the sloping forward surface of the latch head 48 and drives it to the right of Fig. 1 against the pressure of spring 52 to release the latch head from the block 50. The piston 6 is thereupon free to rise and operates to propel the buck upwardly 75

into pressing relationship with the shoe 7. Spring 52 holds latch head 48 slidably in contact with block 50 as the latch rises with the buck. Trip rod 53 may be screw threaded to permit adjustment of the instant of release of latch 47. As the piston 6 rises the ball valve 41 follows it upwardly to close the orifice 43. The small area of orifice 43 renders the unit pressure within chamber 26 ineffective to hold the valve open against the strong bias of its mounting spring 42. The liquid is therefore trapped within the cylinder 30 and acts to prevent counterclockwise movement of the shoe carriage 8. The carriage is thus maintained steadily in registry with the buck as the latter exerts ironing pressure thereagainst.

The return of the buck and shoe to home position is accomplished by opening the motor circuit 12 whereupon the slide valve 28 is driven leftwardly of Fig. 3 by its biasing spring 29 to open the port or ports 27 for the return flow of liquid from chamber 26 to the liquid reservoir. The weight of the piston 6 and its buck is ordinarily sufficient to return the piston to its home position. As the piston head approaches home position the valve 41 will be opened, whereupon the reaction of spring 54 against the shoe carriage will throw the carriage through the angular distance necessary for the center of gravity of the carriage to pass beyond the pivot 11 for completion of the return of the carriage by gravity. Preferably, we establish the center of gravity of the shoe carriage such that a ten degree return rotation under the urging of spring 54 positions the shoe for gravity return. It should be understood that the buck and the shoe carriage may be spring biased for enforced return, if desired. The hydraulic system provides an ever-available shock absorbing system so that even using powerful spring means to drive the elements to home position the return to said position will be without shock or jar.

It will be observed that latch 47 will not reseat until shortly after the shoe carriage 8 begins its return movement, because of the continuing engagement between rod 53 and the latch head during the piston stroke. The operator may "bump" the buck against the shoe by de-energizing and then quickly re-energizing the pump motor after bringing the buck initially into ironing position. Such "bumping" operation, when skillfully done, will in some instances improve the ironing of the articles.

While we have shown a particular embodiment of our invention, it will be understood, of course, that we do not wish to be limited thereto since many modifications may be made; and we therefore contemplate by the appended claims to cover any such modifications as fall within the true spirit and scope of our invention.

What we claim as new and desire to secure by Letters Patent of the United States is:

1. An ironing machine comprising a pair of mutually cooperating press elements individually adapted to be brought from a home position to an operating position, means for simultaneously biasing said elements into movement toward their respective operating positions, means for releasably holding one of said elements against movement, and means operated by said other element upon movement thereof to release said holding means.

2. An ironing machine comprising a frame, a buck, means for supporting said buck for movement from a home position to an operative position, a shoe, means for supporting said shoe for

movement from a home position to an operative position for cooperation with said buck, means common to said buck-supporting and said shoe-supporting means to bias the same simultaneously toward their respective operating positions, means releasably holding said buck against movement, and cam means operated upon movement of said shoe to release said holding means.

3. An ironing machine comprising a frame, a cylinder supported thereon, a piston in said cylinder, a buck on said piston, means for driving said piston in said cylinder, a shoe, a shoe carriage pivoted relative to the buck and swingable in a plane transversely thereof to bring the shoe into registry with said buck, means actuated by said piston-driving means to bring the shoe carriage into said registering position, means for temporarily holding said buck against movement relative to said cylinder during operation of said piston-driving means, and means carried by said shoe carriage to release said buck-holding means upon movement of said shoe carriage to a predetermined position.

4. An ironing machine comprising a frame, a cylinder supported thereon, a piston in said cylinder, a buck on said piston, means for driving said piston in said cylinder, a shoe, a shoe carriage pivoted relative to the buck and swingable to position the shoe in registry with said buck, means actuated by said piston-driving means to bring the shoe carriage into said registering position, a latch carried by said buck and engageable with said frame to hold the buck against movement relative to said frame, and means operated by said shoe carriage during its movement to said registering position to effect the release of said latch to allow movement of said buck.

5. An ironing machine comprising a frame, a cylinder supported thereon, a piston in said cylinder, a buck on said piston, hydraulic pressure generating means in said cylinder to propel the piston therein, a shoe, a shoe carriage pivoted relative to the buck and swingable to a position in which the shoe will be in registry with the buck, means for bringing said shoe carriage into said registering position, a latch carried by said buck and engageable with said frame to hold the buck against movement relative to said frame, and means mounted on said carriage for releasing said latch at the completion of a predetermined movement of said shoe carriage.

6. An ironing machine comprising a frame, a cylinder supported thereon, a piston in said cylinder, a buck on said piston to be moved thereby from a retracted position to a pressing position, means for propelling said piston, latch means between said frame and said buck to hold the buck against the efforts of said piston-propelling means, means for automatically rendering said latch effective at each return of the piston to retracted position, a shoe, a shoe carriage for movement relative to said buck, means for bringing said carriage into position with the shoe in registry with said buck, and means on said shoe carriage for striking said latch to release the same as the carriage is brought into said registering position.

7. An ironing machine comprising a frame, a cylinder supported thereon, a piston in said cylinder, a buck on said piston, means for introducing hydraulic pressure into said cylinder ahead of the piston to propel the same, a shoe, a shoe carriage pivoted relative to the buck and swingable in a plane transversely thereof to bring the

shoe into registry with the buck, a second cylinder fixed relative to the frame, a piston therein, means interconnecting said cylinders to feed said second cylinder with fluid under pressure from the first cylinder for driving said second piston, means connecting said second piston and said shoe carriage for operation of said carriage thereby, means for holding said buck against movement during operation of the second piston, and means effective as the shoe carriage comes into registering position to release the buck for operation of the first piston.

8. An ironing machine comprising a frame, a cylinder supported therein, a piston in said cylinder, a buck on said piston, means for discharging fluid under pressure forwardly of said piston to propel the same from a home position to an operating position, a shoe, a carriage for said shoe and arranged to be propelled from a home position to an operating position, a second cylinder fixed relative to said frame, a piston in said cylinder and connected to said carriage for bringing the carriage into operating position, conduit means interconnecting said cylinders to feed said second cylinder with fluid to operate the piston therein, check valve means in said conduit to bar return flow of fluid from said second cylinder, means operated by the first piston when in home position to open said check valve means, means for releasably holding said piston in home position, and means operated by said shoe carriage to release said holding means after predetermined travel of said carriage, said first piston releasing said check valve means at the commencement of piston travel.

9. An ironing machine comprising a frame, a cylinder supported thereon, a piston in said cylinder, a buck on said piston, means for discharging fluid under pressure forwardly of said piston to propel the same from a home position to an operating position, a shoe, a carriage for said shoe and arranged to be propelled from a home position to an operating position, a second cylinder fixed relative to the frame, a piston in said cylinder for bringing the carriage into operating position, conduit means interconnecting said cylinders to feed said second cylinder with fluid to operate the piston therein, a valve member disposed at the entrance to said conduit and engaged by the piston in said first cylinder to be held open when the piston is in home position, means for releasably holding said piston in home position, means operated by said shoe carriage to release said holding means after predetermined travel of said carriage, and means effective upon release of said valve means following travel of said first piston to close the valve against return flow from said second cylinder.

10. An ironing machine comprising a frame, a cylinder supported therein, a piston in said cylinder, a buck on said piston, means for discharging fluid under pressure forwardly of said piston to propel the same from a home position to an operating position, a shoe, a carriage for said shoe pivoted relative to the buck and swingable to bring the shoe into registry with the buck, a second cylinder fixed relative to the frame, a piston in said cylinder for swinging the carriage into said registering position, conduit means interconnecting said cylinders to feed said second cylinder with fluid to operate the piston therein, valve means in said conduit, means for releasably holding said first piston in home position, means carried by said first piston operable upon movement thereof to home position to

open said valve means, means operated by said shoe carriage to release said holding means after predetermined travel of said carriage, and means responsive to movement of said first piston after the release thereof to close said conduit valve means against return flow of liquid from said second cylinder.
